UNITED STATES PATENT OFFICE.

CLARK S. COMSTOCK, SR., OF EAST ORANGE, NEW JERSEY.

GARMENT-SLIDE.

1,290,914.

Specification of Letters Patent. Patented Jan. 14, 1919.

Application filed October 17, 1916. Serial No. 126,096.

To all whom it may concern:

Be it known that I, CLARK S. COMSTOCK, Sr., a citizen of the United States of America, residing in East Orange, in the county 5 of Essex and State of New Jersey, have invented certain new and useful Improvements in Garment-Slides, of which the following is a specification.

This invention relates to garment slides 10 and aims to provide certain improvements therein.

The invention is particularly directed to a slide for suspender or over-all straps of the type in which the adjustments of the strap 15 are maintained by frictional grip on the slide.

Numerous devices of this character have heretofore been proposed but these have commonly required sewing of the free end of 20 the strap to the middle bar of the slide, or else the formation of a loop at the free end, designed to be afterward engaged with the slide, the middle bar being formed with two parts spaced to permit the insertion of the 25 loop.

According to the present invention I have provided a construction in which the necessity for sewing or the formation of a loop is avoided, the free end of the strap being 30 held by frictional contact solely. To this end I construct a slide in which two middle bars are used, the bars being preferably arranged one above the other in a plane which is approximately perpendicular to the plane 35 of the slide. By this means I provide a slide in which straps of greatly varying thickness may be held by frictional contact alone, with such security as to resist any possible strains in use. At the same time the strap portion 40 which returns from the suspender loop or other similar device secures a much better frictional grip so that the strap holds its adjustments with great tenacity. The invention also includes certain other features 45 of construction which will be hereinafter more fully described.

Referring to the drawings which illustrate several forms of the invention,—

Figure 1 is a plan of the slide detached 50 from the strap;

Fig. 2 is an elevation;

Fig. 3 is a sectional view taken on the line 3—3 of Fig. 1, showing the application of the strap;

Fig. 4 is a plan of a modified form;

Fig. 5 is a similar view of a second modification.

Referring first to Fig. 1 of the drawings, let A indicate the slide as a whole. As shown in this figure it comprises a frame B which is preferably formed of a single piece of wire bent to approximately rectangular shape, the ends of which are shown as joined at C by the formation of two eyes which are interlocked as indicated. 60

Instead of providing a single middle bar as is customary, I provide two bars, D and E which extend lengthwise of the slide as shown, these bars being arranged one over the other and preferably in a plane which is 65 perpendicular to the plane of the frame B, although this exact arrangement need not be adopted. The bars are spaced apart a considerable distance so as to allow the free passage of straps of various thicknesses, that is 70 to say the space is adequate for the maximum thickness of strap. The preferred arrangement of the strap is indicated in Fig. 3, from which it will be seen that the free end of the strap is passed between one side of the frame 75 and the upper bar D, and thence downwardly between the bars D and E. The bight of the strap engages any suitable garment loop such as G, and the return portion H of the strap passes beneath one side of the 80 frame, then over the bar D and thence beneath the other side of the frame. 85

By reason of the arrangement of the bars D and E it will be observed that an extraordinarily secure frictional grip is had upon 90 the end F, and that this grip is not dependent upon the thickness of the strap but works equally well with thick or thin straps. It will be also observed that the bar over which the return portion H extends is preferably raised above the plane of the frame 95 of the slide so that the angle it describes is more acute than with the slides in common use. For this reason the slide holds its adjusted positions with a greater frictional grip than heretofore and thus also tends to increase the grip of the end portion upon the middle bars. It is characteristic of the invention, however, that this additional gripping force is not necessary to provide 100 a secure grip of the end portion, it being practically impossible to move the latter by any strain in the appropriate direction even when the return portion has not as yet passed through the slide. 105

The bars D and E may be constructed in any suitable manner, but when the slide is formed of wire I prefer to construct the bars of a single piece of wire bent at its middle to engage one end of the frame and its opposite ends being bent around the other end of the frame to form attaching eyes. The side portions of the frame around which the wire passes are preferably bent 10 inwardly, as shown at b.

In the construction shown wherein the frame portion is formed of wire and the ends are joined to the middle of one of the sides, the eyes are preferably arranged so 15 that the side of one of them somewhat restricts the space between the side of the frame and the middle bars, thereby securing the effect of pressing into the strap under strain, thus further assisting the holding of 20 the slide in its adjusted positions.

The slide constructed as thus described may be easily and cheaply formed from two pieces of wire by simple machine operations.

In Fig. 4 I have illustrated a modification 25 in which the joint between the two ends of the frame portion B is placed at the end instead of at one side. In this instance the two sides of the slide which show while the strap is in use present a form which is 30 continuous and free from any break.

It is also possible to construct the slide of the present invention of a single piece of wire and in Fig. 5 I have indicated one form 25 of such construction. The arrangement will be apparent without further description.

While I have shown and described several forms of the invention it will be understood that I do not wish to be limited thereto since

various changes may be made therein without departing from the spirit of the invention. 40

What I claim is:—

1. A garment slide comprising a closed rigid wire frame, and two cross-bars of wire spaced apart in a plane substantially perpendicular to the plane of said frame, said wire forming the cross-bars having portions bent around opposite sides of said frame, said wire cross-bars being fixedly connected to said frame. 45

2. A garment slide comprising a closed rigid wire frame, and two cross-bars of wire spaced apart in a plane substantially perpendicular to the plane of said frame, said wire forming the cross-bars having portions 55 bent around opposite sides of said frame, said wire cross-bars being fixedly connected to said frame, said frame being bent inwardly at the sides where the cross-bars are attached. 60

3. A garment slide comprising a closed rigid wire frame, and two cross-bars of wire spaced apart in a plane substantially perpendicular to the plane of said frame, said wire forming the cross-bars having portions 65 bent around opposite sides of said frame, said wire cross-bars being fixedly connected to said frame, said frame and cross-bars being formed of a single piece of wire. 60

In witness whereof I have hereunto signed 70 my name in the presence of two subscribing witnesses.
